UNITED STATES PATENT OFFICE.

AUSTIN R. DODGE, OF SCHENECTADY, NEW YORK, ASSIGNOR TO GENERAL ELECTRIC COMPANY, A CORPORATION OF NEW YORK.

ELASTIC-FLUID TURBINE.

SPECIFICATION forming part of Letters Patent No. 790,426, dated May 23, 1905.

Application filed April 24, 1903. Serial No. 154,075.

To all whom it may concern:

Be it known that I, AUSTIN R. DODGE, a citizen of the United States, residing at Schenectady, county of Schenectady, State of New York, have invented certain new and useful Improvements in the Construction of Elastic-Fluid Turbines, of which the following is a specification.

It has heretofore been considered necessary to enlarge the working passage in elastic-fluid turbines of the jet type from the receiving to the discharge end, meaning by "working passage" the passage formed between the rows of moving and stationary buckets. This enlargement may take place gradually or by a series of steps. In addition to this the nozzle is arranged to enlarge or expand from the throat to the end, so as to largely convert the pressure of the motive fluid into velocity or *vis viva* before delivering it in the form of a jet to the wheel. The enlargement in the working passage involves an increased cost in construction both as to material and in the labor and expense involved in cutting the buckets. The expense of cutting buckets with expanding or enlarging passages between them is largely increased by the fact that a second cut or operation is made necessary where the expansion takes place circumferentially, as is the common practice. The passages between buckets of a given row also commonly increase in radial depth from the inlet to the discharge end, thereby necessitating an inclined peripheral surface, which obviously increases the difficulty of machining besides requiring more metal. In certain instances the enlargement in the working passage forms a very considerable amount of the total area of the passage.

I have determined by a series of tests that the leakage through the clearances between the moving and stationary expanding buckets of the working passage when the clearances are those commonly employed equals the amount of steam which is intended to be taken care of by the enlargement of the passages. Such being the case, some of the bucket-passages in front of the nozzle are

working with less than the necessary amount of steam to fill them. It follows from this that the enlargement is not only unnecessary under the conditions specified, but is a positive objection.

In elastic-fluid turbines there is always considerable condensation of the steam or other motive fluid employed. This is particularly true of jet-machines, where the pressure of the fluid is largely converted into velocity by expanding nozzles before being delivered to the wheels. There is also more or less condensation due to radiation. Obviously the condensation of the steam or other vapor further decreases its volume, which is another reason for not using expanding working passages.

My invention has for its object to reduce the cost and simplify the construction of elastic-fluid turbines and also to render them more efficient.

In the accompanying drawings, which represent one embodiment of my invention, Figure 1 is a quarter-section of a turbine, and Fig. 2 is a detail view showing the construction of the buckets and the nozzle.

1 represents a suitable shell or casing for the wheel 2 and having an exhaust-opening 1^a. The wheel in the present instance comprises two disks, that are secured to a hub 3 by bolts 4. The hub 3 is keyed to a shaft 80 and is secured in place thereon by a nut or equivalent means. Near the periphery the disks are provided with spacers 5 and retaining-bolts 6, which pass through them. Formed integral with the disks or otherwise secured thereto are peripheral buckets 7, having small projections or tenons 8 for securing the segmental cover 9 in place, and between the buckets in a given row are non-expanding passages. Situated between the wheel-buckets is a segmental intermediate support 10, having a plurality of radially-extending buckets 11, also having non-expanding passages between them. The intermediate support is provided with a flange 12, by which it is secured to the casing or shell by bolts 13.

The arc covered by the intermediates varies with the arc of the wheel covered by the noz-

zle or nozzle-sections, and the number of nozzles or nozzle-sections employed is determined by the amount of power which the turbine is to deliver. Between the bodies of 5 the bolts and the support is a slight clearance, which permits the intermediates to be adjusted in a direction parallel with the axis of rotation. The left-hand side of the casing is provided with an opening to receive the expanding nozzle 15. The nozzle is provided with an outwardly-extending flange which engages with a finished surface on the casing. Engaging with this flange is a second flange 10 16, to which the steam-carrying conduit 17 is attached. Bolts 18 are employed to secure both the conduit and the nozzle in place. The nozzle is provided with a well-rounded bowl 19 and a cylindrical restricted throat 20. From the throat to the discharge end of the 15 nozzle the walls diverge, and owing to this divergence the pressure of the steam is converted into velocity or *vis viva* prior to being discharged to the bucket-wheels.

The drawings shown may represent a turbine in itself, or they may represent one stage of a turbine comprising a plurality of stages. The nozzle may consist of one or several similar expanding passages having the same angle of delivery. In the event of the structure shown 25 being used alone the pressure in the conduit 17 will be approximately that of the vapor-generator and the pressure at the discharge end of the nozzle will be somewhat above that of the shell-pressure. In event of the structure 30 shown being used in connection with another stage or stages the pressure within the conduit 17 will be equal to that of its source of supply, whether it be the boiler or an adjacent stage, and the pressure within the shell or casing 35 will be dependent upon what follows the turbine—that is to say, whether it is connected to a second stage or to a condenser or exhausts into the open air. In any event the pressure within the conduit 17 is partly converted into 40 velocity before being delivered to the bucket-wheels. The spaces between the wheel-buckets 8 and the intermediate buckets 11 form a non-expanding working passage for 45 fractionally abstracting the velocity from the motive fluid. In using the term "non-expanding passage" I do not mean to be restricted to a passage which has absolutely the 50 same cross-section at every point, because a slight variation at one or more points will 55 work no substantial injury.

From Fig. 1 of the drawings it will be seen that the entrance and discharge ends of the passages between the wheel-buckets have the same radial depth. The same is true also of 60 the passages between the intermediate buckets. Referring to Fig. 2, it will be seen that the walls 21 and 22 of the buckets are concentric. Hence the cross-section at all 65 points in the working passage is the same. In this manner a non-expanding working

passage is provided for fractionally abstracting the velocity from the motive fluid, which velocity is due to the expanding nozzle 15. By having the radial depth of all of the buckets 70 the same and making the periphery thereof a cylinder instead of the frustum of a cone, as is the common practice, I am enabled to materially decrease the cost of cutting the buckets, because they can be cut at a single 75 operation, whereas when the buckets are provided with passages expanding or enlarging circumferentially it is necessary to alter the position of the tool relative to the work before making a second cut. In this latter case the first cut makes the walls concentric, and 80 the second cut gives the necessary enlargement and makes the walls non-concentric. By dispensing with the enlargement the increase in radial depth of the buckets on their discharge end is obviated, which means a 85 saving in the cost of cutting, because the linear inches cut are less, and also means a saving in stock. This latter is advantageous, because it slightly reduces the weight of the wheel. It must be remembered that the 90 wheel is traveling at high peripheral speed and is under tremendous strain, due to centrifugal force. Hence any saving in weight at the periphery is important.

I have stated that the buckets can be made 95 with a single cut; but I do not wish to be understood as excluding a second or finishing cut, if it is found desirable.

As constructed the nozzle imparts a high velocity to the elastic fluid, which may be 100 steam or similar fluid, and the impact of the molecules on the wheel-buckets causes rotation. Where a single row of wheel-buckets is employed, the speed of the wheel is impractical for ordinary commercial use without 105 expensive and specially-formed speed-reducing appliances; but by providing two or more rows of wheel-buckets and intermediates the speed of the wheel relative to the speed of the fluid stream can be made much 110 lower. This reduction in speed is due to the fact that the velocity of the fluid is abstracted in two or more successive operations, each 115 operation reducing the speed of the fluid stream by a certain amount.

In Fig. 2 the clearance 23 between the wheel and intermediate buckets is clearly shown, and it is evident that so long as the pressure in the nozzle is above the shell-pressure steam will escape radially and be lost in 120 so far as the particular shell is concerned. The clearance between parts is necessary for mechanical reasons, and I so proportion or design the working passages that they are always completely filled with steam when opposite the nozzle.

In accordance with the provisions of the patent statutes I have described the principle of operation of my invention, together 125 with the apparatus which I now consider to 130

represent the best embodiment thereof; but I desire to have it understood that the apparatus shown is only illustrative and that the invention may be carried out by other means.

5 What I claim as new, and desire to secure by Letters Patent of the United States, is—

1. In an elastic-fluid turbine, the combination of an expanding nozzle for converting the pressure of the motive fluid into velocity and discharging it in the form of a jet with its velocity unimpaired, with rows of wheel-buckets separated by clearances through which leakage may take place and which are acted upon by the motive fluid for fractionally abstracting the velocity, the said buckets being separated by non-expanding working passages.

15 2. In an elastic-fluid turbine, the combina-

tion of a shell or casing, bucket-wheels having non-expanding working passages and acting to fractionally abstract the velocity of the motive fluid, intermediate buckets also having non-expanding passages, the wheel and intermediate buckets being provided with clearances through which leakage 20 may take place, and an expanding nozzle which converts the pressure of the motive fluid into velocity and delivers it in the form of a jet to the wheel-buckets.

In witness whereof I have hereunto set my hand this 20th day of April, 1903.

AUSTIN R. DODGE.
